UNITED STATES PATENT OFFICE.

FREDERICK E. KEY, OF ST. LOUIS, MISSOURI, ASSIGNOR TO KEY BOILER EQUIPMENT COMPANY, OF ST. LOUIS, MISSOURI, A CORPORATION OF MISSOURI.

BOILER PLUG.

Application filed April 1, 1920. Serial No. 370,540.

To all whom it may concern:

Be it known that I, FREDERICK E. KEY, a citizen of the United States of America, a resident of the city of St. Louis, in the 5 State of Missouri, have invented certain new and useful Improvements in Boiler Plugs, of which the following is a full, clear, and exact description, reference being had to the accompanying drawings, forming 10 a part of this specification.

This invention relates to improvements in boiler plugs, the main object being to produce a highly efficient means for forming an absolutely tight seal at the opening 15 to be closed. Another object is to produce a plug of this kind which is not liable to be unseated by the pressure in the boiler. A further object is to provide an efficient 20 boiler plug having a number of different elements, all of which can be very easily applied to and removed from a boiler.

With the foregoing and other objects in view, the invention comprises the novel construction, combination and arrangement of 25 parts hereinafter more specifically described and illustrated in the accompanying drawings wherein is shown the preferred embodiment of the invention. However, it is to be understood that the invention comprehends changes, variations and modifications 30 which come within the scope of the claims hereunto appended.

Fig. I is an elevation showing the inner 35 face of a boiler wall and the inner end of the plug.

Fig. II is a vertical section of the elements shown in Fig. I.

Fig. III is a section on the line III—III, Fig. II.

Fig. IV is a detail view suggesting the manner in which the spreader can be inserted from the outside of the boiler.

1 designates a boiler wall provided with 45 a hole 2 adapted to be closed by my boiler plug. To illustrate the preferred form of the invention I have shown a plug, or closure, consisting of four different elements, viz, a spreader A, a thrust member in the form of a ring B, a sealing ring C, and a 50 nut D.

The spreader A is provided with a taper 55 face 3 which lies within the hole 2 so as to be engaged by the inner margin of the sealing ring C. Oppositely disposed flanges 4, 60 extending from the spreader, lie within the

boiler and engage the inner face of the boiler wall as shown in Fig. II. A stud 5 extends outwardly from the spreader A, and it is preferably formed integral with the spreader.

The outer end of the sealing ring C is engaged by the thrust ring B, while the inner margin of the sealing ring lies entirely within the hole 2, where it is interposed between and in contact with the face of the hole and the tapered portion of the spreader. By referring to Fig. II it will be seen that the nut D may be tightened on stud 5 with the result of forcing thrust member B toward the spreader wall. When this occurs, the sealing ring C will be firmly forced onto tapered face 3 of the spreader, whereby the inner margin of the sealing ring is expanded slightly and forced into contact with the face of the hole in the boiler. The sealing ring, which is made of relatively soft metal such as soft steel, is thus expanded on the tapered face of the spreader and at the same time firmly seated against the face of the hole in the boiler so as to form an absolutely tight and leak-proof seal. The wedging action at the inner margin of the sealing ring compensates for any slight depressions, or irregularities, which are usually found in the face of the hole or in the tapered face of the spreader.

In tightening the nut D, the thrust ring B will tend to turn with the nut, and a movement of this kind is undesirable, for the thrust ring should not impart rotary motion to the sealing ring C, and the spreader A should not be permitted to turn with the nut D. Any suitable means may be employed to prevent independent rotation of the spreader A and thrust ring B, for example, the stud 5 may be provided with a non-circular portion 5' and the thrust member B may be provided with a non-circular hole 5^a (Fig. III) adapted to receive said non-circular portion. The thrust member is thus slidably mounted on the stud 5 and interlocked therewith to prevent independent rotation of the spreader and thrust member. The thrust member B may be provided with flat faces 6, as shown in Fig. III adapted to receive a wrench, whereby the thrust member may be held while the nut D is tightened.

All of the parts can be applied and removed from the outside of the boiler. The

flanges 4 on spreader A will pass through the hole when the spreader is tilted and properly manipulated as suggested by Fig. IV, and all the other parts are very easily applied from the outside of the boiler.

The inner margin of sealing ring C is very firmly wedged between the tapered outer face of the spreader and the inner face of the hole. This feature is quite important, for it enables a very tight seal to be produced at the inner end of the sealing ring, and at the same time enables the sealing ring to be easily removed from the boiler. If the inner margin of the sealing ring were not located entirely within the hole, in other words, if the ring passed entirely through the hole and extended from the inner face of the boiler, said sealing ring would be mutilated by the expanding operation and it would be extremely difficult to remove said ring. A highly efficient seal is obtained by the new combination and arrangement of elements, and all of the elements, including the sealing ring, can be very easily removed from the outside of the boiler.

The hole 2 in the boiler wall is preferably tapered, as shown in Fig. II, to permit free removal of the sealing ring C. The tapered face 3 of the spreader lies at an angle to the tapered face of the hole to provide converging faces between which the sealing ring is wedged in such a manner that it can be afterward easily withdrawn from the hole.

The sealing ring C can be re-used a number of times, for it is not mutilated or destroyed by the operation whereby it is tightened in the hole, nor by the operation of removing the ring from the hole.

The seal is formed at the inner margin of the sealing ring, and the inner end of this ring is subjected to the boiler pressure, but this pressure cannot displace the ring. Instead of relying upon friction at the inner margin of the ring to prevent displacement thereof, the sealing ring is positively anchored in the following manner. The flanges 4 on the spreader A cooperate with the inner face of the boiler wall to prevent outward displacement of the spreader, and since the stud 5 is formed integral with the spreader, the thrust member B will cooperate with nut D to prevent outward displacement of the sealing ring C. Therefore, the flanges 4 cooperate with other elements of the combination to positively prevent outward displacement of sealing ring C when the latter is subjected to the boiler pressure.

In tightening the nut D, the spreader A is held in a fixed position by its flanges 4 which then engage the inner face of the boiler wall, while the thrust member B is forced toward the boiler wall for the purpose of wedging the inner margin of ring C into frictional contact with the face of the hole.

Although the inner margin of the sealing ring lies entirely within the hole the outer margin of said ring preferably extends outwardly from the outer face of the boiler wall to receive the thrust member B which is separated from the outer face of said wall. The thrust member B is preferably recessed to receive and closely confine the extended outer margin of the sealing ring, said thrust member having an annular flange 7 surrounding and closely fitted to said extended outer margin. The flange 7 cooperates with the sealing ring C to locate and retain the several elements in their proper relative positions during the period immediately before the tightening of the sealing ring, so when the sealing ring contacts with the tapered faces 2 and 3, the axis of said ring will lie parallel with the axis of the hole. The flange 7 also serves as a reinforcing element for the outer margin of the sealing ring C.

I claim:

1. In a closure for tapered holes in boiler walls, a tapered spreader comprising a head having a tapered portion located within the hole to be closed, the largest diameter of said tapered portion being smaller than the diameter of the hole, said spreader also having flanges adapted to pass through the hole and engage the inner face of the boiler wall to prevent outward displacement of the spreader, the spreader taper being at an angle to the tapered face of the hole so as to provide the converging faces, a sealing ring having its inner margin entirely within the hole to be closed, said inner margin being interposed between and in contact with said converging faces of the hole and spreader, the outer margin of said sealing ring being extended from the wall of the boiler, a thrust member seated on the outer edge of said sealing ring and provided with an annular reinforcing flange overlapping and closely fitted to the extended outer margin of the sealing ring, a screw threaded stud formed integral with and extending outwardly from said spreader, the periphery of said spreader being so small that the spreader can be tilted and inserted through the hole without displacing the screw threaded stud relative to the spreader, said stud having a non-circular portion and said thrust member being slidably mounted thereon to prevent independent rotation of said thrust member and spreader, and a nut on said stud, said thrust member being movable toward the wall of the boiler in response to rotation of the nut so as to force said inner margin of the sealing ring into firm contact with said converging faces.

2. In a closure for holes in boiler walls, a tapered spreader comprising a head having a tapered portion located within the hole to be closed, the largest diameter of said tapered portion being smaller than the diameter of

the hole, said spreader also having flanges adapted to pass through the hole and engage the inner face of the boiler wall to prevent outward displacement of the spreader, the 5 spreader taper being at an angle to the face of the hole so as to provide the converging faces, a sealing ring having its inner margin entirely within the hole to be closed, said inner margin being interposed between and 10 in contact with said converging faces of the hole and spreader, the outer margin of said sealing ring being extended from the wall of the boiler, a stud rigid with and extending outwardly from said spreader, the periphery 15 of said spreader being so small that the spreader can be tilted and inserted through

the hole without displacing the spreader relative to the rigid stud, a thrust member slidably mounted on said stud and engaging said sealing ring, and a nut mounted on said stud 20 and engaging said thrust member, said thrust member being provided with an annular recess into which the outer portion of said sealing ring extends, a wall of said recess overlapping the outer peripheral face of 25 said sealing ring and being closely fitted to said outer peripheral face of said sealing ring so as to aline the sealing ring with the spreader.

In testimony that I claim the foregoing I 30 hereunto affix my signature.

FREDERICK E. KEY.
